ATTORNEYS

UNITED STATES PATENT OFFICE.

CHARLES LOHRMAN, OF WANTAGH, NEW YORK.

RECEPTACLE.

Application filed April 19, 1923. Serial No. 633,274.

To all whom it may concern:

Be it known that I, CHARLES LOHRMAN, a citizen of the United States, and a resident of Wantagh, Long Island, in the county of 5 Nassau and State of New York, have invented new and useful Improvements in Receptacles, of which the following is a full, clear, and exact description.

This invention relates particularly to receptacles constructed of sheet material, as corrugated paper board, and preferably provides such a receptacle constructed of a folded-up unitary blank of sheet material.

An object of the invention is to provide a blank so designed that the one blank may be folded up to provide a receptacle having a plurality of separate, individually accessible compartments, preferably two such compartments, each compartment spaced from 10 the other by a party-wall preferably running medially of the receptacle, preferably of two-ply thickness and preferably about half as high as the outer walls of the receptacle parallel to said party-wall; and a receptacle, 15 further, in which a flap-cover means for the receptacle is provided by the same blank, said cover means preferably including a plurality of leaves of the blank each having a pair of sections one foldable relative to the other, preferably in such a way that the terminal sections may be wedgingly tucked into the interior of the receptacle to dispose said sections in face-to-face contact to constitute 20 them a fully complementary two-ply continuation of said party-wall.

Another object is to provide such a blank, and one so designed that the cutting thereof and the cutting of it and a plurality of its fellows will result in a minimum of waste 25 material but with each such blank adapted to be folded to form a receptacle as just described and a receptacle having one, several, or all of the preferential features indicated.

A further object of the invention is to 30 provide a structure for a blank as last described, such that a multiplicity of blanks of different dimensional characteristics may be provided, but preferably in each case for folding up into a receptacle having a total 35 interior of greater length than width or height, and such then that the blank, when folded up to have a plurality of compartments each as long as the maximum length of said total interior, may be folded to pre-

sent individual cover means for each compartment so established that such cover means constitute roof closures for all the compartments, in one case when the receptacle is arranged to dispose its maximum dimension horizontally, and in another case 60 when the receptacle is arranged to dispose its maximum dimension vertically.

Still a further object of the invention is to provide a receptacle itself, whether constructed of a unitary blank or not, but having a party-wall between two of its compartments, which party-wall preferably of two-ply thickness throughout, includes a pair of wall sections arranged edge-to-edge preferably adapted to be maintained in such edge-to-edge relation by the wedging action of 70 adjacent parts of the receptacle.

Another object of the invention is to provide a blank, and a receptacle made from one or more blanks, pursuant to the last two 75 paragraphs, such that the same generally characteristic type of blank, as to similarity of outline, relation of sections, and scoring or fold lines, may be employed for the making of a receptacle of larger size, to 80 constitute the compartment-carrying or main receptacle, as an egg-box case for parcels-post, and for the making of a receptacle of smaller size, to constitute a compartment-receiving or minor receptacle, as an egg-wrap- 85 per box for reception by each compartment of such egg-box case.

However, from the three paragraphs foregoing, it will be understood that the invention, even as now understood and appraised, 90 is capable of a multitude of uses for transporting various classes of articles, and particularly fragile articles, such as radio-bulbs, delicate measuring instruments, bottled mineral water and other glass devices or 95 containers, as by parcels-post, hand-portage, or otherwise.

Various other objects and advantages of the invention will be in part obvious and in part specifically referred to hereinafter.

The invention will be more clearly understood from the following description, when taken in connection with the accompanying drawings, illustrating, but merely by way of example, receptacle combinations, one such combination for transporting, say by parcels-post, a large number of eggs, and another such combination for facilitating the

conveyance, say by hand-portage, of a collection of such dissimilar commodities as a plurality of soft-drink bottles.

In said drawings,

Fig. 1 shows a unitary blank for a carrier for eggs, before being folded up;

Fig. 2 is a perspective view of the blank of Fig. 1 in process of being folded up to establish the receptacle of Fig. 3;

10 Fig. 3 is a perspective view of the receptacle last mentioned;

Figure 4 is a transverse sectional view, on an enlarged scale, taken on line 4—4 of Figure 3.

15 Referring now to Figs. 1 to 4:

These views shows a blank, and the minor receptacle made therefrom, and the at present intended purpose of the latter in regard to providing its two compartments 20 each for accommodating a line of eggs. It will be understood that such minor receptacle will be received in each of the compartments of main receptacle.

Referring to Fig. 4 such eggs are shown 25 arranged in two parallel columns C' and D', each column floatingly accommodated in one of the elongated compartments C and D established within the minor receptacle; and preferably with the columns of eggs in 30 separate pockets c and d forming parts of a singles cardboard wrapper of a familiar type and having nothing to do with the present invention except in regard to illustrating its ready adaptability for co-operation 35 with accepted and approved egg-wrappers already on the market. As is well-known, the egg wrapper C—D just mentioned, when closed about its two columns of eggs as shown and described, is tied together, to 40 establish the pockets c and d each of oval cross-section as illustrated, by a plurality of spaced girthing strings one of which is shown at e in Fig. 4.

Now, by examining the blank of Fig. 1 45 it will be seen, that it includes a first section 30, a second section 31, a third section

32, a fourth section 35, these parts to form the girthing side walls of the receptacle of Figs. 2 and 3, bottom wall flaps 38 and 40 (which may be provided with an adhesive), flap portions 20 and 22, 21 and 23, 24 and 26 and 25 and 27, and suitable score-lines and slits. It will be seen, too, from Fig. 3, that here an extra gummed piece of flexible material 36" may be used. It 50 will finally be seen, from Fig. 4, after a cross-comparison with Figs. 1 and 2, that here, too, flap portions 20, 21, 24 and 25 co-act to form a bracing and rigidifying interior or party-wall while notches 45° not only receive the horizontal stretches of 55 strings e but co-act with such strings to hold the double-ovate egg wrapper somewhat resiliently and shock-absorbingly to its appointed accommodation within compartments C and D of the minor receptacle. 60

It will be understood, from what precedes, that the showing of the drawings, and the parts herein described, are merely illustrative, and not to be taken as limiting in any 70 way a carrying out of the invention pursuant to the following claim; in connection with which claim it will be understood that variations may be freely resorted to within the spirit and scope of the invention. 75

I claim:

A receptacle, comprising a body made from a blank having sides and ends and provided with a flap extending from each side at top and bottom and of a width 80 equal to one half the width of the receptacle, each flap having a right angular terminal portion provided with a notch in its longitudinal edge and extending into the receptacle, the terminal portions of the top flaps being in alinement with the terminal portions of the bottom flaps and the terminal portions of the top and bottom flaps being in engagement with each other to form 85 a two-ply wall dividing the receptacle into two compartments.

CHARLES LOHRMAN,
